AIR PUMP

Filed Sept. 8, 1924

FIG. 3

FIG. 2

INVENTOR
HENRY J. WEPPLO
By Paul, Paul & Moore
ATTORNEYS

UNITED STATES PATENT OFFICE.

HENRY J. WEPPLO, OF MINNEAPOLIS, MINNESOTA.

AIR PUMP.

Application filed September 8, 1924. Serial No. 736,626.

This invention relates to improvements in air pumps and more particularly to such pumps of the hand-operated reciprocating type such as are commonly employed in connection with automobiles to inflate the usual pneumatic tires thereof.

The particular object of this invention is to provide a manually-operated reciprocating air pump having means thereon whereby the operator may employ foot-power to downwardly force the reciprocating piston thereof to pump air into a tire or other device.

A further and more specific object of the invention is to provide such a pump having a foot pedal and hand grip reciprocally mounted thereon and operatively connected to the pump rod thereof, so that the downward or power stroke of the piston may be effected by foot pressure and the suction stroke accomplished by hand power, thereby greatly increasing the efficiency of the pump.

A further object of the invention is to provide a combined hand and foot pump-operating mechanism particularly adaptable for use in conjunction with reciprocating pumps, and which mechanism may also be used as an attachment to convert an ordinary hand-operated pump into a foot-operated pump, the necessary changes required to make such a conversion being practically minimized.

A further object of the invention is to provide such a device of simple and inexpensive construction which comprises very few parts and may therefore be manufactured at a minimum cost.

Other objects of the invention will appear from the following description and the accompanying drawings and will be pointed out in the annexed claims.

In the accompanying drawings forming a part of this specification,

Figure 1 is a view in side elevation of a reciprocating pump showing my invention applied thereto;

Figure 2 is a sectional plan on the line 2-2 of Figure 1; and

Figure 3 is a detail sectional view on the line 3-3 of Figure 1.

In the selected embodiment of the invention here shown there is illustrated a reciprocating air pump of ordinary construction, comprising a cylindrical tube or cylinder 5 having a pump rod 6 reciprocally mounted

therein. The usual leather cup or piston 7 is suitably secured to the lower end of the rod 6 as shown in Figure 1, and a head 8 is secured to the upper end of the cylinder 6 to form a closure therefor and also a guide 60 for the rod 6. The cylinder is preferably mounted in a base 9 having an outwardly extending end portion 11 provided thereon to form a support for the pump when in operation. A pivotally mounted supporting member 12, preferably constructed of heavy wire or rod and U-shaped in form, is provided on the opposite side of the cylinder. The terminals 13 of this supporting member are preferably inwardly bent and fitted into 70 opposed sockets provided in a hub 14, as shown in Figure 2, so that the member may be upwardly folded against the side of the cylinder as indicated in dotted lines in Figure 1, when the pump is not in use. When 75 the supporting member 12 is extended as shown in full lines, Figure 1, it provides a step for the operator to place his foot upon to support the pump when being operated.

A feature of this invention resides in the 80 novel means provided for reciprocally actuating the pump rod 6 when pumping air into a tire or other device. Such means preferably consists in the provision of an auxiliary rod 15 having its upper central 85 portion connected to the upper end of the pump rod 6 by means of a U-shaped clip or clevis 16 which is suitably secured to the rod by such means as welding. As shown in Figure 3, a pin 17 connects the clevis 16 to 90 the pump rod 6. The lower portion of the rod 15 has a loop 18 secured thereto which is adapted to encircle the cylinder 5 and thereby provide a guide for the lower end of the rod. An outwardly extending step 95 19 having its outer end 21 preferably upwardly bent as shown, is provided on the lower end of the rod 15 and functions as a step or pedal for the operator to place his foot upon to downwardly force the pump rod 6 in the operation of the pump. A hand grip 22 is provided at the upper end of the rod 15 so that the operator may grasp the rod to upwardly lift it to raise the piston 7 during the suction stroke of the pump. The 100 usual hose connection 23, having a coupling 24 for connection with a tire or other device, is connected to the base 9 and communicates with the interior of the piston.

In the operation of this novel pump it 110

will be positioned as shown in Figure 1, with the U-shaped supporting member 12 extended so that the operator may place one foot thereupon. The operator will then grasp the hand-grip 22 of the auxiliary rod 15 and lift it, and therefore the pump rod 6 and piston 7, until the step 19 will be substantially in the position shown in dotted lines, Figure 1. He will then place his other foot upon the step 19 and downwardly force it to the position shown in full lines, thereby forcing the air, drawn into the pump by the suction stroke, through the hose connection 23 and into the tire or other device being inflated. Thus, it will be seen that the suction stroke of the pump will be performed by hand power, that is, the rod and piston will be lifted by hand to draw air into the pump cylinder, and the air thus drawn into the cylinder will be expelled therefrom by downward pressure of the operator's foot upon the step 19. Also, if desired, the operator may bear down upon the hand-grip 22 when downwardly forcing the piston by means of the step 19, thereby increasing the power applied to the pump rod. By the provision of the step 19 in conjunction with a reciprocating air pump the efficiency of such a pump will be considerably increased as a result of the operator being able to apply greater power or force to the downward or pressure stroke of the piston 7. A pump provided with such a step may therefore be operated with less effort and with greater convenience than the ordinary type of hand-operated pump such as are now in common use.

The combined hand and foot pump-operating mechanism here shown may also be used as an ordinary hand pump if desired by simply reciprocating the rod 15 and therefore the pump rod 16 by means of the hand-grip 22. It may also be used as an attachment for reciprocating pumps of ordinary construction by simply removing the usual hand-grip provided on such a pump and securing the clip 16 to the upper end thereof and fitting the loop 18 to the cylinder thereof in the manner shown in the accompanying drawing.

In the construction of this novel pump the cylinder 5 is preferably arranged at a slight angle in the base 9 so that when pressure is applied to the rod 15 at the side of the pump, the pump will be more stable in operation. By thus arranging the cylinder 5 in the base 9 there will also be less danger

of the operator's knee striking the upper portion of the pump when operating it.

In the drawings there has been disclosed a structure designed to carry out the various objects of the invention but it is to be understood that the invention is not confined to the exact features shown as various changes may be made within the scope of the claims which follow.

I claim as my invention:

1. The combination with a base, a pump barrel mounted thereon and having a plunger, and an attachment for operating the plunger, comprising a rod having an integral loop at its lower end mounted to slide on said barrel, and having step and hand grip portions respectively at the bottom and top and extending in the same direction, said rod connected at an intermediate point to the plunger by an arm extending in a direction opposite to the step and hand portions.

2. The combination with a pump barrel and plunger therefor, and a rod within said barrel attached to said plunger, of a rod outside said barrel having a loop to encircle and slide on said barrel, and a clip for attachment to said plunger rod, the lower end of the rod outside said barrel having a step thereon forming a foot-piece to allow the user of the pump to apply the foot thereto and aid in depressing the plunger in said barrel, the upper end of the rod outside said barrel having a hand-grip and normally projecting above said barrel.

3. The combination with a pump barrel and plunger therefor and a rod within said barrel attached to said plunger, of an operating rod formed independently of said pump rod and mounted to slide on the walls of said pump barrel and adjacent thereto, the lower end of said operating rod having an angularly formed step thereon to receive the foot of the operator, the upper end of said operating rod projecting above said barrel and having a hand grip within convenient reach of the operator, said operating rod below said hand grip being adjacent to the upper end of said plunger rod and having means for connection therewith to insure simultaneous uniform movement of said rods, downward pressure of the hand and foot of the operator on said operating rod being transmitted directly to said plunger rod.

In witness whereof, I have hereunto set my hand this 5th day of September 1924.

HENRY J. WEPPLO.
